UNITED STATES PATENT OFFICE.

JOSEPH A. BUTTRESS, OF LOS ANGELES, CALIFORNIA.

CURVE-SCRIBER.

1,216,066.

Specification of Letters Patent. Patented Feb. 13, 1917.

Application filed April 17, 1916. Serial No. 91,622.

To all whom it may concern:

Be it known that I, JOSEPH A. BUTTRESS, a citizen of the United States, residing at Los Angeles, in the county of Los Angeles, 5 State of California, have invented new and useful Improvements in Curve-Scribers, of which the following is a specification.

This invention relates to devices for scrib- 10 ing curved lines; and it is a primary object of this invention to provide a universal curve scribe in simple and economical form; and it is a further object of this invention to provide a curve scribe which may be easily set and adjusted to any given curve 15 and which facilitates the easy and accurate drawing of such curves.

Further objects of my invention are made to appear in the following specification wherein I describe a preferred form of my 20 improved curve scribe. This preferred form of scribe embodies a longitudinal bar having a series of spaced notches in its under edge, and a flexible preferably metallic strip adapted by proper placement in 25 said notches to be flexed and held in the desired curvature or curvatures. So far as the fundamentals of my invention are concerned the above described parts are the two essential parts. In order, however, to make 30 a universal instrument I provide a third part in the form of a cross bar adjustable in position on the longitudinal bar and adjustable as to transverse projection from the longitudinal bar; it being the office of this 35 cross bar to hold any point of the flexible strip in any desired definite position relative to the longitudinal bar. I also provide the scribe in such form, and also provide a special means in the form of a center point, 40 so that the scribe may be readily used for drawing sets of curves symmetrical with respect to an axis or center point.

I now proceed to a detailed description of my preferred form of scribe and refer to 45 the accompanying drawings in which Figure 1 is a plan of my improved scribe; Fig. 2 is a side elevation of the same without the cross bar; Fig. 3 is an enlarged partial bottom plan; Figs. 4, 5, 6, 7, 8, 9 and 50 10 are enlarged cross sections showing various forms of the longitudinal bar; Fig. 11 is an enlarged section showing a preferred construction of the flexible strip; Fig. 12 is 55 an enlarged detail section taken as indicated by line 12—12 on Fig. 1; Fig. 13 is an enlarged detail view taken as indicated

by line 13—13 on Fig. 1; Fig. 14 is an enlarged detail section taken as indicated by line 14—14 on Fig. 1; Fig. 15 is a plan showing the scribe with a center point; 60 Fig. 16 is a side elevation of the same; Fig. 17 is a section taken as indicated by line 17—17 on Fig. 16; Fig. 18 shows a typical symmetrical design made with my scribe; Fig. 19 is a section and Fig. 20 a side elevation showing a modified form of means for mounting the center point on the longitudinal bar; and Figs. 21 and 22 are sections showing modified forms of the flexible strip. 65

In the drawings I show a longitudinal 70 bar 10 which may be of any desired length. This bar may be of many cross sectional forms, as illustrated by the cross sectional configurations shown in Figs. 4 to 10. A typical form of the bar is that shown in 75 Figs. 4 to 7 and 10, wherein the bar is an inverted channel having an upper web 11, 11^a, 11^b, 11^c or 11^d and has downwardly extending side flanges 12, 12^a, 12^b, 12^c or 12^d. The notches 13 are cut in the side flanges; 80 and these notches are preferably formed as is shown in Fig. 3. It is desired to form the notches not of uniform width from face to face of the side flanges of the channel, but wider on one face than on the other, 85 so as to facilitate the diagonal placement of the flexible strip through the notches. These notches may be placed exactly opposite each other and evenly spaced throughout the length of the bar, as is shown in some por- 90 tions of Fig. 3. The flexible strip 15 may be placed at right angles across the longitudinal bar 10, as is shown in dotted lines at the right of Fig. 3, or it may be placed diagonally across the bar as is shown in 95 the center portion of Fig. 3. The peculiar form of the notches 13 above referred to facilitates this diagonal placement without widening the notches so much that the strip is excessively loose when placed square 100 across the bar. It will be noted that I have shown the notches wider at their outer edges than at their inner edges; and I attain this formation of the notches without the necessity of specially cutting and press- 105 ing them in this form by the expedient of concaving the material between the notches, as is shown at 16; the result of this concaving being to draw the edges of the notches to the positions shown so as to make 110 the notches wider outside than inside. The effective widths of the notches as regards

square placement of the strip is thus unchanged while their effective clear widths with regard to diagonal placement of the strip is materially increased. Consequently, 5 with a longitudinal bar having the notches arranged squarely opposite each other, I am able to place the flexible strip either in position squarely across the bar as is shown at the points marked 15^a in Fig. 1, or I may 10 place the flexible strip diagonally across the bar as at the points shown at 15^b in Fig. 1. The angle of diagonal placement depends upon the width of notch, the thickness of the flexible strip, the width of the bar itself, 15 and the spacings between notches.

In a preferred form of the bar 10 I provide a series of notches 13^a, 13^b, 13^c, 13^d arranged not opposite each other but at various angles across the bar as is clearly illustrated in Fig. 3. I may provide the center part of the bar with squarely arranged notches, and then on each side of this center part provide a set of the angularly arranged notches, and then outside of the angular sets provide again the squarely arranged notches. The flexible strip may be placed at any desired angle in the angular notches; and the provision of two sets of angular notches makes it possible to place 20 the strip, with reference to the bar, at actual opposite angles at points symmetrical with relation to the center of the bar.

With the illustrated arrangement of notches the flexible strip may be curved and 25 held in almost any desired position to form any given curve or set of curves. Fig. 1 illustrates what can be done with the squarely arranged notches alone; and with the use of the angularly arranged notches 30 the variety of positions and curvatures is greatly increased. The strip may be flexed into as long or as short a curve as desired. I provide with my instrument a number of differently flexible strips; and in a preferred 35 form I may provide one strip formed by three very thin spring steel bands, another formed of two slightly thicker bands (shown in Fig. 11) and another formed of a single steel band. The first mentioned form of 40 band is very flexible and may be bent to form very short curves; while the last mentioned form is comparatively stiff and is used for long curves, the stiffness providing for a firm drawing edge not easily displaced 45 by pressure of pen or pencil. By providing sets of flexible strips of different stiffnesses I provide for the smooth formation of short, medium or long curves. The natural resiliency of the bands makes them assume 50 smooth and unbroken, continuous curves without any breaks—without any humps or flat points. In Figs. 21 and 22 I have shown formations of flexible strips for ink work. In Fig. 21 I show two steel bands 70 and 55 71, one of lesser width than the other so that

the lower edge of the narrower band will stand above the drawing surface. In Fig. 22 I show the single steel band 73 equipped with a narrow outstanding strip 74 of any suitable material, as hard rubber, spring 70 steel, etc. This narrow strip 74 may be secured to the band 73 in any suitable manner; it may be secured by mechanical holding means or may be cemented or brazed onto the band 73; or the strip 74 may be formed integrally with the band 73 as a longitudinal offset from said band. 75

As I have hereinbefore stated, the bar may have various cross sectional forms. In Fig. 4 I have shown a plain inverted channel; in Fig. 5 a channel having a sunk web 11^a and inwardly converging side flanges 12^a; in Fig. 6 a plain channel having grooves 20 formed in its flanges near the top; in Fig. 7 a channel having an outwardly rounded bead 25 21 at its top. In Fig. 10 I have shown the plain channel and have shown the concavities 16 between the notches 13. In Fig. 8 I show a bar 10 in the form of a hollow square tube; and in Fig. 9 a solid form of bar. 90 The upper flat surfaces of any of these forms may carry the designating numerals 25. These numerals preferably proceed from zero at the center of the bar; and the numerals thus facilitate the formation of curves 95 symmetrical with relation to the transverse center axis of the bar. Curves symmetrical with relation to any axis may be drawn by turning the scribe end for end or by turning the scribe bottom side up. It will be 100 seen, by reference to Fig. 2, that the flexible strip 15 extends very nearly to the top of the bar 10; so that the whole device may be turned over and the normally upper edge of the curved strip will then be close enough to 105 the drawing surface to facilitate easy drafting of a curve symmetrical to that drawn with the scribe in its normal position. However, in this relation, it may be stated that symmetrical curves may always be 110 drawn by replacing the flexible strip in opposite position, symmetrical with its former position with relation to the bar; the flexible strip being at all times easily placed in any 115 required curvature and position.

I have hereinbefore referred to the cross bar 30. This cross bar 30 has on its outer end a foot 31 having notches 32 adapted to engage the flexible strip 15. The cross bar is mounted in a suitable clamp 33 and held 120 in any set position by thumb screw 34. This thumb screw presses the cross bar down onto the ends 35^a of clamping dogs 35 pivoted centrally at 36 to the clamp 33. The lower ends 35^b of dogs 35, are shaped to conform 125 to the cross sectional conformation of the bar 10, as is clearly shown in Fig. 14. Downward pressure by screw 34 not only holds the cross bar 30 immovable but clamps the dogs 35 onto bar 10. A slight loosening of the 130

clamp screw will allow the cross bar to be adjusted in position without loosening the dogs sufficiently to allow the bar 30 to be accidentally moved along bar 10. Transverse adjustment of the bar 30 is the means of adjusting the position of any point, as the point 15^c, of flexible strip 15. In Fig. 1 I have shown the flexible strip being held to a flat curve by the transverse bar. Many other uses of the transverse bar will occur to those skilled in the art or those using the scribe.

I have hereinbefore described the use of my curve scribe for the making of curves or duplicate curves symmetrical with respect to any axis. I provide means for making sets of curves symmetrical with relation to a center. In Figs. 15, 16, 17 and 18 I illustrate my device for such purposes. In Figs. 15, 20 16 and 17 I show the longitudinal bar 10 equipped with a downwardly projecting center pin or point 50. This center pin may be mounted upon the bar 10 in any desired manner; but I prefer to mount the pin adjustable and movable along the bar. This may be easily done by providing a small slide 51 in the form of a clamp having a thumb screw 52 to set it in any given position, the center pin 50 projecting from the 30 under side of the clamp 51. The center pin projects below the plane of the lower edge of flexible strip 15 as is clearly shown in Fig. 16. Or the center pin may be mounted on the bar by means of a spring clasp 60 as shown in Fig. 20. In this case the center pin 50^a is integral with a flat key 61 adapted to enter one of the notches 13 to register the pin opposite any notch.

In Fig. 18 I have shown an example of work that may be done with a scribe equipped with this center pin. To make the figure illustrated the center pin is put in the position on the bar shown in full lines in Fig. 15. The center pin is then set on the 45 drawing surface at the center point (designated in Fig. 18 by the small circle denoted 53), and the scribe being set in any given position, one of the curves 54 is drawn. The scribe is then rotated about the center pin 53 through any given angle and the next curve is drawn; and so on until the complete design is made. It will be readily apparent that a great variety of designs may be made by scribing curves about a common center. 55 For instance, the center point may be placed near one end of the bar 10, as indicated in dotted lines in Fig. 15 and an entirely different figure will then result. Series of volatile or other curves may be drawn about a 60 center; and the instrument with its center point facilitates very much the drafting of such mechanical elements as gear teeth, impeller blades, etc.

The simplicity of my curve scribe is 65 readily seen; and I have described how the

scriber may be easily and quickly adjusted to a great variety of curves and how it may be used for drawing symmetrical curves or designs. Once the flexible strip is placed in position in the bar it is not easily accidentally displaced from its set position. The tension induced by curving the strip holds the strip against the edges of the notches. In its function of securely holding the strip against accidental displacement the channel shaped bar plays an important part. The provision of opposite notches through which the strip passes provides for a certain binding action on the strip which is not attained in a plain bar.

Having described a preferred form of my invention, I claim:

1. A curve scribe embodying a bar having transverse notches across its underface extending up into the bar, and a flexible strip adapted to fit into the notches.

2. A curve scribe embodying a bar having transverse evenly spaced notches across the under face extending up into the bar on one face, and a flexible strip adapted to fit into the notches.

3. A curve scribe embodying a channel-shaped bar having spaced notches in its side flanges, said notches being wider on one face of the flanges than on the other, and a flexible strip adapted to enter the notches.

4. A curve scribe embodying a channel-shaped bar having spaced notches in its side flanges, the flanges between the spaced notches being concaved so as to form them wider on one face of the flanges than on the other, and a flexible strip adapted to enter the notches.

5. A curve scribe embodying a channel-shaped bar having spaced notches in its side flanges, the notches in one flange being arranged in definite opposite relation to the notches in the other flange, and a flexible strip adapted to fit into the notches.

6. A curve scribe embodying a channel-shaped bar having spaced notches in its side flanges, a portion of said notches being arranged so that the notches in one flange are opposite the notches in the other and another portion being arranged so that individual notches in one flange and individual notches in the other flange are on lines diagonal to the length of the bar, and a flexible strip adapted to fit into the notches.

7. A curve scribe embodying a channel-shaped bar having spaced notches in its side flanges, the notches in one flange being arranged in definite opposite relation to the notches in the other flange, each of said notches being wider on one face of the flange than on the other, and a flexible strip adapted to fit into the notches.

8. A curve scribe embodying a channel-shaped bar having spaced notches in its side flanges, a portion of said notches being ar-

- ranged so that the notches in one flange are opposite the notches in the other and another portion being arranged so that individual notches in one flange and individual notches in the other flange are on lines diagonal to the length of the bar, each of said notches being wider on one face of the flange than on the other, and a flexible strip adapted to fit into the notches.
10. 9. A curve scribe embodying a channel-shaped bar having spaced notches in its side flanges, the notches in one flange being arranged in definite opposite relation to the notches in the other flange, the flanges being concaved between the spaced notches so that the notches are formed wider on one face of the flanges than on the other, and a flexible strip adapted to fit into the notches.
10. 10. A curve scribe embodying a channel-shaped bar having spaced notches in its side flanges, a portion of said notches being arranged so that the notches in one flange are opposite the notches in the other and another portion being arranged so that individual notches in one flange and individual notches in the other flange are on lines diagonal to the length of the bar, the flanges being concaved between the spaced notches so that the notches are formed wider on one face of the flanges than on the other, and a flexible strip adapted to fit into the notches.
10. 11. A curve scribe, embodying in combination a longitudinal bar having spaced transverse notches on one edge, a flexible strip adapted to enter said notches, and a transverse bar adapted to engage the flexible strip and having means for adjustable mounting on the longitudinal bar.
10. 12. A curve scribe, embodying in combination a longitudinal channel-shaped bar having spaced notches in its side flanges, a portion of said notches being arranged so that the notches in one flange are opposite the notches in the other and another portion being arranged so that individual notches in one flange and individual notches in the other flange are on lines diagonal to the length of the bar; the flanges being concaved between the spaced notches so that the notches are formed wider on one face of the flanges than on the other, and a flexible strip adapted to fit into the notches.
15. 13. A curve scribe embodying a flexible strip, a bar having means for engaging and holding the strip, and a center point on the bar adapted to engage a drawing surface to form a center about which the bar and strip may be rotated.
15. 14. A curve scribe embodying a flexible strip, a bar having means for engaging and holding the strip, and a center point longitudinally adjustable on the bar adapted to engage a drawing surface to form a center about which the bar and strip may be rotated.
15. 15. In combination, a bar having spaced notches, a flexible strip adapted to enter the notches, and a center point on the bar adapted to engage a drawing surface to form a center about which the bar and strip may be rotated.
15. 16. In combination, a bar having spaced notches on its under side extending vertically up into the bar, a flat flexible strip adapted to enter the notches and be thereby held in flexed position, and a center point longitudinally adjustable on the bar and projecting downwardly beyond the plane of the lower edge of the strip.
15. 17. A curve scribe embodying a bar having transverse notches across its under face extending up into the bar, said notches lying in vertical planes making various horizontal angles with the length of the bar, and a flexible strip adapted to fit up into the notches.
- In witness that I claim the foregoing I have hereunto subscribed my name this 12th day of April 1916.
- JOSEPH A. BUTTRESS.
